(57) **CLAIM**

The ornamental design for a portable display device, as shown and described.

DESCRIPTION

FIG. 1 is a front perspective view of a portable display device showing our new design in a first embodiment; FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a front perspective view of a portable display device showing our new design in a second embodiment; FIG. 9 is a front view thereof;

FIG. 10 is a back view thereof;

FIG. 11 is a left side view thereof;

FIG. 12 is a right side view thereof;

FIG. 13 is a top view thereof; and,

FIG. 14 is a bottom view thereof.

The broken lines in FIGS. 7 and 14 and the lower opacity areas within the broken lines show portions of the portable display device that form no part of the claimed design.

1 Claim, 8 Drawing Sheets
